CLAIM

The ornamental design for a condenser, as shown and described.

DESCRIPTION

FIG. 1 is a perspective view of a condenser showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The wire frame lines shown throughout the views are intended to indicate surface contour.

The broken lines are directed to environment and form no part of the claimed design.
